UNITED STATES PATENT OFFICE.

WILFRED B. GODDARD, OF SAN FRANCISCO, CALIFORNIA, ASSIGNOR TO THOMAS DAY COMPANY, OF SAN FRANCISCO, CALIFORNIA, A CORPORATION OF CALIFORNIA.

DESIGN FOR A BOBECHE OR ADAPTER FOR LIGHTING FIXTURES.

Application filed January 31, 1925. Serial No. 12,211. Term of patent 7 years.

To all whom it may concern:

Be it known that I, WILFRED B. GODDARD, a citizen of the United States, and a resident of the city and county of San Francisco, State of California, have invented a new, original, and ornamental Design for a Bobeche or Adapter for Lighting Fixtures, of which the following is a specification, reference being had to the accompanying drawings, forming part thereof.

In said drawings—

Figure 1 is a plan view, and

Figure 2 is a side elevation of the bobeche or adapter for lighting fixtures illustrating my new design.

I claim:

The ornamental design for a bobeche or adapter for lighting fixtures, substantially as shown.

WILFRED B. GODDARD.
